UNITED STATES PATENT OFFICE.

ANDREW H. RUSSELL, OF WATERTOWN, MASSACHUSETTS.

BREECH-LOADING ORDNANCE.

SPECIFICATION forming part of Letters Patent No. 236,363, dated January 4, 1881.

Application filed November 6, 1880. (No model.)

To all whom it may concern:

Be it known that I, ANDREW H. RUSSELL, of Watertown, in the county of Middlesex and State of Massachusetts, have invented certain new and useful Improvements in Breech-Loading Guns, of which the following is a full, clear, and exact description.

This invention relates to the French system of "fermeture," so known. Under this system the breech is open in the axial line of the bore of the gun, and is screw-threaded, and constructed together with a correspondingly-threaded screw-plug for the latter to be directly inserted within the screw-threaded chamber of the breech, and then, by being turned therein, engaged and interlocked against accidental movement and escape. In the use of this system of fermeture it is customary, in the loading of the gun, to cover the screw-thread of the threaded breech with what is known as a "pan" or "apron," so that no injury can come to the thread of the breech as the projectile is inserted, which pan, after the projectile is inserted, is removed, and then the breech-plug inserted and turned, and, thus locked, closing the breech.

The main purpose of this invention is to obviate the necessity of the removal of the pan or apron protector to the screw-threaded breech before the breech-plug can be inserted; and to that end it consists of a pan or apron so constructed in itself and in combination with the breech-plug as not only to give the necessary and desired protection to the threaded breech when the projectile is being inserted, but, when the breech-plug is inserted, to interlock with and become a part of it and turn with it as it is turned to lock it in place and against accidental movement and escape, all substantially as hereinafter described.

In addition to the above, this invention consists in mechanism for holding or locking the pan against accidental movement within and escape from the breech as the projectile is inserted, and in a construction of the breech-plug to automatically unlock the pan as it is inserted, so that it may turn with the breech-plug, as before stated, all substantially as hereinafter described.

In the accompanying plate of drawings my improvements in breech-loading guns are illustrated, Figure 1 being a view, in perspective,

at the breech and open end of the gun, with the pan and breech-plug detached; and Figs. 2 and 3, respectively, perspective views of the 55 pan and breech-plug removed; Fig. 4, a longitudinal vertical section through the axial line of the bore of the gun, showing the breech-plug and pan in their position before the plug is turned to lock it in the breech; Figs. 5 and 6, cross-sections on line x x , Fig. 4, the one with the breech-plug and pan in the position shown in Fig. 4, and the other with the breech-plug and pan after being turned to lock the plug in position within the breech; Fig. 7, a 65 longitudinal vertical section through the axial line of the bore of the gun, showing the pan constructed to be held or locked against accidental movement within and escape from the breech, and the breech-plug as constructed to 70 automatically unlock the pan as it is inserted; and Fig. 8 is an end view of the same.

In the drawings, A represents the breech portion of a gun. This breech is open at its rear end, a , along the axial line of the bore of the 75 gun, and it has a female screw-thread, b , which is cut out in parallel lines, making square-sided channels c , which run in the length of the bore, leaving sections d of the screw-thread between the channels c , one of which sections 80 is at and along the lowermost part of the breech-opening.

B is the breech-plug. This breech-plug has a male screw-thread, f , corresponding to the female screw-thread b of the breech-opening, 85 and along its length portions of its screw-thread are cut out, as at g , corresponding in position to the threaded sections d of the breech-chamber, the whole so that the plug can be inserted directly within the breech-opening, and then, by being turned, its threaded 90 portions interlocked with the threaded portions of the breech, and thus the plug locked and secured in place, all as heretofore in the French system of fermeture.

h is the pan or apron. This pan or apron covers the lowermost threaded section of the breech-opening, and, as shown in Fig. 3, it is provided with a screw-thread corresponding to the screw-thread of the breech-opening. In addition to this it is shaped to fit within one of the cut-out portions g of the screw-threaded breech-plug B, and thus it is adapted to be interlocked and engaged therewith. This pan or

apron, placed as described, obviously protects the screw-threaded breech in its portion covered by it from injury when a projectile is inserted; and again, when the breech-plug is afterward inserted, it interlocks with the breech-plug, so that when the breech-plug is turned to unlock it, as ordinarily, the pan or apron moves with it, and, in substance, as if in one part and piece with it, (the breech-plug.) It is thus seen that the necessity of removing the pan after the projectile is inserted and before the breech-plug can be inserted is wholly obviated. This pan or apron may or may not have a screw-thread to fit the threaded breech, it being shown without such a thread in Fig. 7.

In Fig. 7, *l* is a spring-catch, situated at the outer end of the pan, and there arranged and adapted to interlock with a notch, *m*, at the end of the breech. This spring-catch *l* holds the pan from rolling within the open breech as the projectile and breech-plug are inserted.

n is a radial flange or projection at the outer end of the breech-plug, and in position thereon to abut against the spring-catch *l*, and thus release its hold of the pan when the breech-plug is inserted within the breech. By this means the pan is automatically released to the turning movement of the breech-plug.

o o² are flanges at each end of the pan. By one, *o*, of these flanges the inner end of the pan interlocks with the screw-threaded breech at its innermost end, it being there suitably and correspondingly constructed therefor. The other flange, *o²*, fits over and lies against the outer face of the end of the breech, and thus by it and the inner interlocking flange, *o*, the pan is held from movement along the length of the breech during the insertion of the projectile and of the breech-plug, while at the same time they offer no obstruction to the turning of the pan with the breech-plug as the latter is turned.

It is obvious from the within description of the pan *h* and its arrangement in relation to the breech-opening and breech-plug, that when the plug is out the pan can be readily and easily removed and replaced at pleasure, and, further, that when in place not only does it serve as a guard to the threaded portion of the breech-opening which it covers, but it acts as a guide and bed on which to slide the pro-

jectile into place, and thus obviates all possibility of injury to the remaining screw-threaded portions of the breech-opening.

The locking of the pan against turning, substantially as herein described, may be employed either with or without a construction of the pan and of the breech-plug to interlock the two, so as to turn as one when the breech-plug is turned to lock it in place, and the same is true as to the interlocking of the pan with the breech-opening to secure it against longitudinal movement therein.

Having thus described my invention, what I claim, and desire to secure by Letters Patent, is—

1. The combination, in a breech-loading gun, of a breech, *A*, and a breech-block, *B*, each constructed with a sectional screw-thread, substantially as described, with a pan or apron, *h*, serving as a guard for a portion of the screw-threaded breech, and constructed to interlock and rotate with the breech-block when the latter is screwed into the breech-piece, essentially as set forth. 75

2. The combination, in a breech-loading gun, of a breech, *A*, having an internal sectional screw-thread, a breech-block, *B*, having an external sectional screw-thread, a pan or apron, *h*, serving as a guard for a portion of the screw-thread in the breech, and mechanism operated from the exterior of the breech for locking the pan in position to prevent it from turning as the projectile is inserted, substantially as described. 80

3. The combination, in a breech-loading gun, of the sectionally screw-threaded breech *A*, the sectionally screw-threaded breech-block *B*, the apron or pan *h*, constructed to set over a portion of the screw-thread in the breech, and mechanism, substantially as described, for automatically locking and unlocking the apron or pan by the movement of the breech block, essentially as and for the purpose set forth. 85

In testimony whereof I have hereunto set my hand in the presence of two subscribing witnesses.

ANDREW H. RUSSELL.
